UNITED STATES PATENT OFFICE.

GUSTAV KUEBLER, OF SAGINAW, MICHIGAN.

OVEN.

SPECIFICATION forming part of Letters Patent No. 771,877, dated October 11, 1904.

Application filed April 29, 1904. Serial No. 205,592. (No model.)

To all whom it may concern:

Be it known that I, GUSTAV KUEBLER, a subject of the Emperor of Germany, residing at Saginaw, county of Saginaw, and State of Michigan, have invented certain new and useful Improvements in Ovens, of which the following is a specification.

My invention relates particularly to baking-ovens of the class in which draw-plates are employed which are mounted to slide horizontally into and out of the oven. These plates when drawn out for setting or drawing a batch have heretofore been supported outside the oven by stationary frames or by supports carried by the plates and resting on the ground or on rails outside the oven.

The object of my invention is to provide means wholly within the oven for supporting the draw-plates in any position to which they may be moved.

In carrying out my invention I provide each oven with fixed longitudinal rails which serve as guides for horizontally-sliding rails and which securely and firmly hold said sliding rails in a horizontal position both when they are inclosed in the oven and when they are withdrawn therefrom to the desired extent for setting or drawing a batch. Anti-friction devices, such as balls, are interposed between the sliding rails and the fixed rails, and suitable stops are employed to limit the movements of the balls and the rails relatively to each other. Each set of sliding rails supports a draw-plate or tray which is mounted to slide longitudinally or horizontally on the rails.

My improvements are especially designed for use in what are known "as draw-plate baking-ovens;" but they may be used in baking-ovens and drying-ovens of various types.

In the drawings, Figure 1 shows a longitudinal section of a draw-plate oven embodying my improvements on the line 1 1 of Fig. 2. Fig. 2 shows a transverse section thereof on the line 2 2 of Fig. 1. Figs. 3 and 4 are detail views, on an enlarged scale, showing particularly the manner in which the draw-plate is carried and the sliding rails are supported and guided. Fig. 5 is a plan view of

the sliding rails connected by cross-pieces and which support the draw-plate. Figs. 6 to 10, inclusive, show a modified form of an oven constructed in accordance with my invention. Fig. 6 shows a longitudinal section on the line 6 6 of Fig. 7. Fig. 7 shows a transverse section on the line 7 7 of Fig. 6. Fig. 8 is a detail view, on an enlarged scale and in section, showing the manner of supporting and guiding the draw-plate and sliding rails. Fig. 9 shows a vertical section on the line 9 9 of Fig. 8. Fig. 10 is a plan view of the sliding rails connected by cross-pieces. Fig. 11 is a detail view in cross-section, showing a further modification.

The walls A of the oven and the chambers and flues therein may be constructed in any suitable way. They form no part of my present invention. I have shown a double-deck oven, the baking-chambers B being shown one over the other; but any suitable number of baking-chambers may be employed, and they may be arranged in various ways. In Figs. 1 and 2 I have shown each baking-chamber as being provided with two longitudinal guide-rails C, preferably made of channel-beams arranged longitudinally in recesses in the two opposite side walls of the oven with their parallel upper and lower flanges c projecting toward the interior of the oven. These beams constitute guides for a frame D, consisting of two parallel rails d, connected by cross-pieces d' and held thereby such a distance apart that the rails d are held within the channel-beams, as clearly shown in Figs. 2 and 3. Preferably the flanges c of the beams are provided with strips E, grooved to receive anti-friction devices, such as balls F, and provided with stops e to limit the movement of the balls. The rails d are provided with similar grooved strips d', and they are provided with stops d' to limit the movement of the balls and to at times engage the balls and carry them against the stops e in the manner hereinafter explained. Each frame B carries a draw-plate or tray G, of ordinary form, but which, as shown, is provided on its under side with strips g, formed with stops g'. Each tray rests on two axles H, carrying wheels h,

that enter the rails d and are free to move longitudinally therein to an extent limited by stops d^5 on the inside of their lower flanges. The channel-beams C are located, preferably, 5 about midway between the top and bottom of the baking-chamber, leaving ample space around the trays for the free circulation of hot air. The trays move freely on the rails and are out of contact with the walls of the 10 chambers at all times.

It will be observed by reference to Fig. 1 that when the sliding rails are drawn out they are firmly and securely held in a horizontal position solely by the fixed guide-rails C . There 15 are no outside supports, and the rails do not come in contact with other parts of the oven. It will also be observed in Fig. 1 that the upper tray G is entirely outside the oven and is supported solely by the rails. Fig. 1 also 20 shows the position of the several parts when the rails and draw-plate or tray have been moved back into the baking-chamber. It will be observed that none of the parts project beyond the oven-door, and there are no supports, 25 rails, or other fixtures outside the oven.

In order that the trays may be supported when drawn, it is necessary that the sliding rails should fit closely the fixed guide-rails and that stops should be provided to limit 30 their outward movement, so that a sufficient portion of each rail shall remain within the oven to prevent the front ends thereof from dropping or moving out of a horizontal position. It will be observed also that the stops 35 which limit the movement of the tray on the rails are so located as to prevent the tray from moving forward to such an extent that there will be any possibility of its being tilted forward by shifting weights, and the stops are 40 also so located as to cause the plates to come to rest when they have been moved rearward to a sufficient extent on the rails. The plates can be very quickly withdrawn or inserted and the antifriction devices permit great freedom 45 of movement. The plates merely rest on the axles H , and therefore are free to move across these axles, while the axles, with their wheels h , are free to move in the sliding rails, and the sliding rails have freedom of movement 50 in the fixed guide-rails. While there is the great freedom of movement above referred to, the stops and balls are so arranged as to prevent undue movement at any time.

While it is preferable to use separate strips 55 E and d^2 to carry the stops, as shown in Figs. 3 and 4, the stops may be formed on or secured to the rails.

In Figs. 6 to 10, inclusive, I have shown a modification. Channel-beams C' are employed; 60 but the flanges c' are embedded in the walls of the oven, and to the outer faces of the channel-beams are secured angle-beams C^2 , having flanges c^3 , arranged one above the other to form guide-rails for the sliding rails

D' . These rails D' are connected by cross-bars D^2 , as indicated in Fig. 10. The rails D' are preferably formed of channel-beams and overlap the flanges c^3 . Antifriction devices, such as balls F , are interposed between the flanges of the rails D' and the flanges c^3 , and 70 stops e' are provided to limit the movement of the balls. Preferably the stops are formed on separate strips E' and C^4 , attached to the rails D' and the flanges c^3 in the manner indicated in Figs. 8 and 9. By this arrangement 75 the rails D' may be moved back and forth on the fixed rails as guides, their upward movement is limited, and they are held securely and firmly in a horizontal position, as shown in Fig. 6, solely by the fixed guide-rails and 80 without the use of external supports. The trays G' instead of resting on axles H in the manner shown in Figs. 1 and 2 rest on anti-friction devices, such as balls F , as shown in Figs. 8 and 9. Preferably strips J are attached to the under side of the trays, and they are provided with stops j , which limit the movement of the trays on the balls. The rails D' are also provided with stops K , which 85 limit the movement of the balls F' . The operation is similar to that before described in connection with Fig. 1.

In Fig. 6 the upper draw-plate is shown outside the oven, while the lower draw-plate is within the oven. When the upper draw-plate 95 is moved back, the front balls F' will be moved against the stops K in rear of them and the further inward movement of the draw-plate on the rails D' is prevented. In like manner when the rails D' are moved inward 100 the front stops at x come in contact with the balls at x' and move these balls rearward to the position shown at x^2 in Fig. 6. The balls at x^3 are moved rearward in a similar 105 way to the position shown at x^4 . In this way freedom of movement is afforded and yet the parts are all properly supported at all times.

Instead of securing the fixed rails to the side walls of the oven they may be removed from the sides and supported at their ends or 110 in any suitable way some distance from the side walls, as indicated in Fig. 11. This is a good arrangement when the draw-plate is 115 very wide, as it prevents sagging of the plate in its central portion.

I am enabled by my improvements to move each draw-plate to a position entirely outside the oven, and the draw-plates may be lifted from the rails and taken away without disturbing the rails, which are supported solely 120 by the fixed guide-rails. When the parts are in the oven, the space at the front of the oven is entirely clear. The parts are so assembled that the draw-plates are held far above the bottom of the oven, so that there may be a 125 free circulation of air around them.

I claim as my invention—

1. An oven provided with fixed longitudi-

- nal rails within it, sliding rails solely supported by said longitudinal rails and held thereby in a horizontal position at all times, and a draw-plate movable with the sliding rails to a position outside the oven, in which position the outer ends of the sliding rails are unsupported. 5
2. An oven having within it fixed longitudinal rails, sliding rails solely supported by said longitudinal rails and held thereby in a horizontal position at all times, antifriction devices both above and below the sliding rails and interposed directly between said sliding rails and the upper and lower faces of the fixed rails, and a draw-plate movable with the sliding rails to a position wholly outside the oven, in which position the sliding rails are unsupported at their outer ends. 10
3. An oven having within it fixed longitudinal rails provided with upper and lower flanges, sliding rails supported solely by said longitudinal rails and guided by said flanges, and antifriction devices interposed directly between the sliding rails and the upper and lower flanges of the fixed rails, and a draw-plate arranged wholly above the fixed rails and sliding rails and supported by said sliding rails. 15
4. An oven having fixed longitudinal rails attached to its side walls, sliding rails supported solely when within the oven or drawn out therefrom by said longitudinal rails, 20
5. An oven having fixed longitudinal rails secured to its side walls, sliding rails supported solely by said fixed rails, when within the oven or drawn out therefrom, cross-bars rigidly connecting said sliding rails with each other and a draw-plate supported by and adapted to slide on said sliding rails. 35
6. An oven having within it fixed longitudinal rails, sliding rails supported solely thereby and held thereby in horizontal position at all times, cross-bars connecting the sliding rails, a draw-plate supported on the sliding rails, and antifriction devices interposed between the moving parts to permit freedom of movement. 40
7. An oven having within it fixed longitudinal rails, sliding rails solely supported at all times by said fixed rails and guided thereby antifriction-wheels supported and guided by said sliding rails, axles to which said wheels are connected, and a draw-plate resting on said axles and free to slide thereon. 45

In testimony whereof I have hereunto subscribed my name.

GUSTAV KUEBLER.
